UNITED STATES PATENT OFFICE.

CHARLES E. MCCLUER, OF RICHMOND, VIRGINIA.

TELEPHONE TOLL-BOX AND CONNECTION-REGISTER.

SPECIFICATION forming part of Letters Patent No. 424,993, dated April 8, 1890.

Application filed May 28, 1889. Serial No. 312,475. (No model.)

To all whom it may concern:

Be it known that I, CHARLES E. MCCLUER, a citizen of the United States, residing at Richmond, in the county of Henrico, State of Virginia, have invented a new and Improved Automatic Telephone Toll-Box and Connection-Register, of which the following is a full, clear, and exact description, reference being had to the accompanying drawings, forming a part of this specification.

My invention is designed to obviate the necessity of telephone patrons having to make fixed annual, quarterly, or monthly payments for their telephone service; or, as is necessary in the ordinary toll system, of requiring a record to be kept by the central-office operators of the connections ordered from each station. The fixed rental system requiring, as it does, regular payments at stated intervals without any reference whatever to the amount of usage of the telephone lines and instruments, is unjust to both the subscribers and the corporations or individuals furnishing the telephone facilities, in that the subscribers are unequally taxed and the owners of the telephone plant are often inadequately remunerated. A subscriber who utilizes his telephone but seldom often pays for his moderate service a larger compensation than others who use their telephones with the utmost frequency, and the proprietors of the telephone systems receive as compensation from large users not infrequently less remuneration than they do from other subscribers or customers who make but a limited use of the telephone facilities afforded them.

In cases where a toll system has been adopted, either in lieu of or in connection with a fixed rental system, it is either necessary for the telephone proprietors to require a record of connections to be kept by their employés or they must trust to the honesty of their patrons. The first alternative is expensive, troublesome, and provocative of disputes, and the latter very apt to result in loss to the proprietors.

My toll-box is intended to remedy the defects and injustice of both the fixed rental and ordinary toll systems by providing a simple and reliable means for enabling each telephone customer to pay for or record his connections as ordered, insuring to the telephone

company a proper remuneration for the service rendered, or providing a correct and reliable record of connections made for each station that company and customer alike can accept as just, thus avoiding disputes.

There are two telephone-exchange systems in use at the present time, one known as the "Law" system, the other as the "magneto" system. The former is economically applicable only to telephone-exchanges consisting of lines of moderate length, because of the necessity of providing a special wire in addition to the usual subscriber's wire commonly denominated a "call" wire, its use being practically restricted to the direct transmission of "calls" or orders for connections without any preliminary signal being given to the central-office operators, while the magneto system requires the provision of only the direct or subscribers' wires, over which it is necessary to send a current of electricity from a voltaic battery, or, preferably, from a magneto-generator, in order to attract the attention of the central-office operator by an audible or visual signal as a preliminary to the transmission over the same wire of an oral order for a connection. My device is thus necessarily applied somewhat differently to these two systems. I will therefore describe them separately in connection with Plates Nos. 1, 2, and 3.

Plates Nos. 1 and 2 represent my device as applied to a Law-system call-bell alone, while Plate No. 3 represents it as applied to both a Law system and a magneto call-bell.

Plate No. 1, Figure 1, represents an ordinary Law system call-bell with the front removed, and showing only as much of the usual appointments as is necessary to an intelligible description of my invention. Figs. 2, 3, and 4, Plate 2, are designed to illustrate the device adopted to prevent the withdrawal of a coin or token after having been used to secure a connection. Figs. 5 and 6, Plate 2, illustrate the action of the automatic stop designed to cause the coin or token to bridge over or "close" a break in the call-wire circuit. Figs. 6 and 7, Plate 2, are intended to make plain the manner in which the coin or token is caused to announce its release from the "automatic" stop by making a "cross" between the call-wire and the direct or sub-

scriber's wire and the means afforded the central-office operator for removing the cross by tripping the coin or token into the money compartment or till. Fig. 8, Plate 2, illustrates the device employed to prevent the removal of the front of the bell-box by unauthorized persons. Fig. 9, Plate 3, shows the application of my device to the Law switch of a Law system call-bell, while Fig. 10, same plate, illustrates its application to the phone-hook of a magneto call-bell.

The same parts in the various figures are lettered alike.

Recurring now to Plate No. 1, Fig. 1, A represents a flat chute or tube just large enough to allow a coin or token of a designated thickness, diameter, and shape to pass through it readily, the tube being provided with openings in its edges and sides, as indicated. B is an escutcheon rigidly attached to the end of the chute or tube A, and to the side of the box and provided with a slit or opening suitable for the admission of the coin or token into the chute or tube A. C is a support for the light metal back-stop D. E is a stationary contact-spring, through which the call-wire is grounded by the coin or token when arrested at the automatic stop F, and G is a movable contact-piece attached to but insulated from the phone-hook H, to which the call-wire is connected. H is the phone-hook, with its retractile spring Q, tending to raise it. I is a stationary contact-piece at one side of the cross-stop J, to which the call-wire is connected, while O is a movable contact-piece connected to the private line at the same stop J, normally extending through the opening K in chute or tube A, but permanently attached to and therefore movable with the armature L, which is attached to a spring M at one end, but free to move at the other. N N are two spools of a small electro-magnet, whose office it is to attract the armature L and withdraw the contact-piece O from the opening K in the chute or tube A.

In Fig. 1, Plate 1, the dotted line to the left, numbered 1, represents the ground-wire connected to stationary contact E. The middle dotted line, numbered 2, represents the call-wire attached to stationary contact I and connected thence to movable contact G, while the dotted line to the right, numbered 3, shows the subscriber's wire connected to movable contact O and continued through the spools of the magnet N to stationary contact E.

In Fig. 9, Plate 3, the dotted lines represent the call-wire attached to movable arm or contact G, and the ground-wire connected to stationary contact E.

In Fig. 10, Plate 3, the dotted lines represent one end of the magneto armature-coil connected to movable contact G, while stationary contact E is connected "to line" or "to earth."

P is the cash-box or money-till forming the final receptacle for the coin or token.

S'' represents the holes in the sides and top of the box for the insertion of the dowel pins in the box-front, represented at S', Fig. 8.

T is the division-piece separating the money box or till from the compartment in which are located the other devices, and Q is the retractile spring attached to the phone-hook.

I will now explain the manner in which the toll-box is used.

Any one desiring to use the telephones must first, as is universally required in Law-system exchanges, remove the hand-phone from its hook, which is represented in its normal position at II, Fig. 5. The weight of the hand-phone being removed from the hook allows the retractile spring Q to raise it to the position shown at II in Fig. 6. This upward movement of the phone-hook throws the movable contact G of automatic stop F from its normal position, as in Fig. 5, in which it entirely clears the chute or tube A into the position represented in Fig. 6, when it reaches entirely across the opening in the chute or tube A. A coin or token now placed in the slit in the escutcheon B, as in Fig. 2, and allowed to pass down the tube A, brushes aside the light back-stop D, as illustrated at R, Fig. 2, but is arrested in its descent at automatic stop F by stationary contact E and the movable contact G, its periphery touching each contact through the openings in the tube A, as represented by the dotted circle at E, F, and G, Fig. 1. Here it will remain as long as the phone-hook H is held in the position indicated in Fig. 6; but the moment the telephone is restored to its normal position on the hook the latter is depressed by its weight and assumes its normal position, as illustrated in Fig. 5, thus withdrawing the movable contact G from the opening at automatic stop F in the chute A, releasing the coin or token and allowing it to continue its descent under the influence of gravity. It, however, encounters another obstacle in its passage through the chute or tube A at the cross-stop J, Fig. 1, where it comes into contact with stationary contact-point I and movable contact O, resting against each of them by its periphery, as it did at the automatic stop F. Here it remains until the electro-magnet N is energized by a current of electricity, when the armature L is attracted by the poles of the electro-magnet N, and the movable contact-point O is withdrawn from its normal position across the tube A at the orifice K, thus removing the last obstacle from the path of the coin or token and allowing it to fall finally into the money box or till P.

As is well known to all Law-system experts, the call-wires in the "tap" or "leg" system are normally "open," while in the "metallic-circuit" call-wire systems the call-box connections are merely "cut out" of circuit. In the former or tap system the depression of the call-wire lever closes the call-wire circuit to that particular station by throwing the call-wire to earth, while in the metallic-circuit

system the depression of the call-wire lever merely "loops" the bell-box connections, including, of course, the telephone and transmitter, into the call-wire circuit. Hence in order to apply my device to the tap system it is only necessary to insert the stationary and movable contacts E and G, Fig. 1, in the call-wire circuit between the usual ground-plate and the earth, while for the metallic-circuit system they can be introduced at any point in the bell-box call-wire loop. It will consequently be necessary in either case to bridge over the break in the continuity of the circuit at the automatic stop F between the contacts E and G by a conducting-body, such as a coin or a metallic token, extending from one to the other through the openings in the tube A. Without thus electrically bridging over the space between the stationary and movable contacts E and G, the call-wire will remain inoperative as far as that station is concerned, and it will be utterly impossible for the person desiring to use the telephone to reach the ear of the central-office operator and make his wants known; but the moment this break in the circuit is closed by the contact of the edges of the metallic coin or token with the two contact-pieces E and G, the call-wire circuit will be closed and rendered operative, and an order for a connection can be heard by the central-office operator. At the cross-stop J the coin or token also electrically bridges the space between stationary contact-piece I and movable contact-piece O, and the call-wire being connected to one, and the private line or subscriber's direct line to the other, through the spring M and armature L, thus creates a cross or an electrical contact between the two and enables the central-office operator to hear in her call-wire head-phone anything passing over the private line.

To fully understand what follows, reference must now be made to United States Patent No. 402,264, issued to C. E. McCluer, the present applicant, April 30, 1889, for an improvement in multiple switch-boards, as that device is utilized to announce to the central-office operator instantly and unmistakably when the phone is replaced upon the hook at the close of a conversation and the coin or token is allowed to drop from the automatic stop F to the cross-stop J, as the moment the coin bridges over the space between the contact-pieces I and O and forms a cross between the call-wire and the subscriber's line the central-office operator instantly hears in her call-wire head-phone the peculiar ticking due to the induced current passing over the subscriber's line from the induction-coil connected up with the flexible cords and connecting-plugs, as is fully explained in the specification and drawings of Patent No. 402,264, alluded to above, such specification and drawings being made, as far as may be necessary, a part of this specification. Hearing in her call-wire head-phone the multiple test indication "line in use," the central-of-

fice operator knows at once that the coin or token is "crossing" the private line with her call-wire, and she at once disconnects the two stations and applies her calling-battery plug to the toll-station line and sends an electrical impulse out on the wire. The two spools of the electro-magnet N, being connected in the private-line circuit "in series" with the call-bell magnet, are energized by the battery-current and the armature L is attracted thereby, the movable contact-point O withdrawn from the orifice K in the chute or tube A, and the coin, having fulfilled its mission, is allowed to drop into the locked till or cash-compartment P. Thus as long as the coin or token is allowed to remain at the automatic stop F, by reason of the user refraining from replacing the phone on the hook H, so long will it continue to bridge over or close the break in the call-wire circuit, and so long will the user be able to repeat his order for a connection; but the phone once replaced upon the hook, or the hook once depressed, the coin is released and moves onto the cross-stop J, rendering the insertion of another coin or token necessary before another order for a connection can be transmitted to the ear of the central-office operator, this fact being rendered apparent to her at once by the ticking from the multiple test induction-coil, which she hears only when the coin or token is resting on the cross-stop J. If, now, she receives from the same toll-station another order for a connection, she at once complies; but if after having made one connection in obedience to an order from a given toll-station, another order is given from the same toll-station for another connection with another and entirely different station, without her having received the indication that the coin used for the transmission of the former order has been released by the depression of the phone-hook and allowed to drop down to the cross or indication stop J, she knows beyond doubt that the same coin or token is being utilized for ordering a second connection, and she declines to make the connection until that coin has been released and another one is inserted.

In order to prevent the withdrawal of a coin or token by means of a thread attachment, after it has been utilized for ordering a connection, the back-stop D, Fig. 1, is provided. This is a light curved strip, preferably of hard metal, loosely hung to a support C in such a manner that in its normal position it hangs close to and covers an opening made in the edge of the tube A, Figs. 1 and 4, a part of the edge of the chute being cut away, as indicated. This swinging piece D is readily pushed aside by a descending coin or token, as represented at R, Fig. 2; but if an attempt is made to withdraw the coin or token by means of a thread attached to it the back-stop D effectually prevents its withdrawal by its lower end engaging with the edge of the coin or token and closing up the chute, as shown at R, Fig. 3.

Fig. 8 is designed to show the device adopted to prevent the front of the box being removed by unauthorized persons. S' represents dowel-pins attached to the box front, and so located as to fit into the holes in the bell-shelf and side pieces S'', Fig. 1. The lower end of the front of the bell-box proper extends to the middle of the thickness of the partition T, dividing the till P from the upper part of the box, and attached to it by screws is an angle-shaped piece of metal U, which fits against the under side of the partition T. Attached to this end of the angular piece of metal U is a metal hook V, which engages with a screw-eye W, screwed into the partition T, inside the till P. The front to the till is attached to the side piece by hinges and closes down upon the angular metal U, and is locked in that position, thus effectually preventing the removal of the front to the toll-box without first gaining access to the money box or till P.

We will now turn to Plate No. 3, in which Fig. 9 represents a modified form of my toll-box device for Law-system stations to be used whenever it is desired, either for the sake of simplicity or because of the non-use or absence of the McCluer multiple test to dispense with the cross-stop represented at J, Fig. 1, Plate No. 1, and described above. Fig. 10 illustrates my device applied to a magneto call-bell.

Looking now at Fig. 9, Plate No. 3, A represents the flat chute or tube; B, the escutcheon; C, the support for the back-stop D; E, the stationary contact of the automatic stop F, and G the movable contact of the same stop; but movable contact G, instead of being attached to the phone-hook, as in the various figures in Plates Nos. 1 and 2, is attached to the call-wire lever H and moves with it. Attached rigidly to the arm of movable contact G is another arm, carrying at its end movable "dead-stop" Z, so adjusted with reference to the openings in the edges of the tube A that when the call-wire lever H is in its normal position, as represented by the solid lines, it will arrest a coin or token passing through the tube A. Here the coin will remain until the call-wire lever is depressed for the purpose of ordering a connection, when the upward and lateral movement of the dead-stop arm throws the attached dead-stop Z away from the opening in the tube A, as indicated by the dotted lines, and allows the coin to continue its descent. At the same time, however, the movable contact G, influenced by the downward motion of the external end of the call-wire lever H, is simultaneously moved toward the opening in the edge of the tube at automatic stop F, its movement being so adjusted and timed with reference to the movement of the dead-stop Z that the coin just released by the dead-stop Z is again arrested at the automatic stop F by engaging with the contacts E and G, contact G having assumed the position indicated by the dotted lines. Here the coin or token will remain as long as the call-wire lever is

held in the depressed position indicated by the dotted lines; but the instant the call-wire lever is released and the retractile spring Q causes it to resume its normal position, as represented by the solid lines, the coin is released and under the influence of gravity finally drops into the receptacle P. In using a toll-box fitted up in this manner it will of course be necessary for the user to hold the call-wire lever down until assured by the central-office operator, in the usual manner, that his order has been heard and is understood, else he will be compelled to insert another coin or token before he can repeat his order. A different coin or token will therefore be required for each order, the office of the coin or token being to close the call-wire circuit between the stationary and movable contacts E and G, as heretofore explained in connection with figures in Plates 1 and 2.

Fig. 10, Plate No. 3, illustrates the application of my toll-box device to a magneto call-bell box. The parts lettered A, B, C, D, E, and F are identical with those similarly lettered in the other figures. G and H are, however, differently arranged. G, the movable contact to automatic stop F, is in the form of an arm attached to but insulated from the phone-hook H, as represented, in such a manner that when the phone is on the hook and the hook is depressed the movable contact G assumes the position indicated by the solid lines, closing up the opening in the tube A and holding the coin or token at the automatic stop F; but immediately the phone is removed from the hook the phone-hook lever H and movable contact-arm G assumes the position indicated by the dotted lines and the coin or token is released and drops into the till P. While in the magneto call-bell the coin or token is intended to close up a break in a circuit between the stationary and movable contacts E and G, as it does in the Law-system toll-box, that break in the circuit, is in the magneto-generator circuit between one end of the armature-coil and the push-button or automatic shunt, so that the generator-circuit will be open, and therefore inoperative unless the open or break in the continuity of the generator or armature circuit is bridged over or closed by the metal coin or token. Unless the space between the stationary contact E and the movable contact G is thus closed by an electrical conductor, the magneto will not ring, and the user consequently cannot call up either the central office or another station.

The front of the magneto toll-box and the door of the money box or till are attached and secured from unauthorized opening in the manner explained above in connection with Fig. 8, Plate No. 2.

Having thus described the scope of my various devices, I claim as my invention, for which I desire to secure Letters Patent—

1. In combination with a telephone bell-box, an escutcheon, and chute or tube, a curved tongue or strip D, swinging loosely in front

of an opening in the edge of the tube A, substantially as and for the purpose described.

2. In combination with a telephone call-bell box, an escutcheon, and a chute or tube, stationary and movable electrical contact-springs arranged within openings in the edges and sides of the chute or tube, the movable contact-springs being attached to and moving with a switch-lever, substantially as and for the purpose described.

3. In combination with a Law system telephone call-bell, an escutcheon and tube, a stationary contact-piece I in electrical connection with the call-wire, and a movable armature L, supporting the contact-piece O, in electrical connection with the subscriber's wire, the two contacts so adjusted with relation to each other as to be capable of being electrically connected through openings in the tube A by a metallic coin or token inserted in the tube, with an electro-magnet N arranged to operate the movable contact-piece O, substantially as and for the purpose described.

4. In connection with a telephone toll-box and call-bell, a front to the bell-box furnished with dowel-pins S' to fit into the holes S'', and a metal piece U, bent at right angles and secured at one end to the inside surface of the box front and the other end passing beneath the partition T, and secured to it by a hook V, engaging with the screw-eye W, with a separate hinged front to the money compartment or till P, closing down upon the right-angled metal piece U, and secured by lock 35 and key, substantially as and for the purpose described.

5. In combination with an escutcheon and a coin tube or chute, fixed and adjustable electrodes arranged within apertures made in 40 the sides and edges of the tube, with a switch-lever attached to and operating the adjustable electrodes, substantially as described.

CHARLES E. MCCLUER.
